UNITED STATES PATENT OFFICE.

JOSEPH H. MURRAY AND MCKINLEY WESSON, OF STRUTHERS, OHIO.

PITCH BURNER.

Application filed May 11, 1921. Serial No. 468,621.

To all whom it may concern:

Be it known that JOSEPH H. MURRAY and MCKINLEY WESSON, citizens of the United States of America, residing at Struthers, in the county of Mahoning and State of Ohio, have invented certain new and useful Improvements in Pitch Burners, of which the following is a specification.

This invention relates to pitch burners adapted to utilize pitch and other similar product which has been a complete or partial waste due to ineffective methods of burning the same.

The principal object of the invention is to take this pitch, or other material, reducing the same to a liquid, then to a semi-gaseous state, where it is thoroughly mixed with forced air.

Another object of the invention is to provide a hopper positioned upon a steam heated base, this base resting upon a water cooled member.

Another object of the invention is to provide water-cooled members situated upon the outer edges of the water cooled member above referred to.

A still further object is to provide a water-cooled adjustable gate to regulate the heat radiating toward the hopper from the furnace proper.

With these and other objects in view the invention consists in the novel arrangements and construction of parts, which will be hereinafter more fully described and set forth in the claim.

Figure 1 is a side elevation of the device showing a portion of the inclosing wall in section; Figure 2 is an end view of the device.

Figure 3 is a detail view of our water cooled member.

Figure 4 is a detail view of the air supply means.

Figure 5 is a detail view of a gate.

By referring to Figure 1 it will be seen that the device may be built so as to rest upon a floor level 1. Upon this floor level 1 there is provided a support structure 2, having side arched openings 3. Resting upon the side support structure 2 is a water cooled member 4. It will be seen that this water cooled member 4 forms an incline with the lower end 5 extending into a combustion chamber 6. This water cooled member 4 is provided with the intake and outlet pipe 7.

By referring to Figure 2 it will be seen that there is located upon the water cooled member 4 two water cooled members 8. Centrally located upon the water cooled member 4 is a steam heated base 9 provided with inlet and outlet openings 10. Positioned upon this steam heated base 9 is a pitch hopper 11 which is provided with an opening 12 facing the furnace. In front of this opening 12 there is a gate 13 provided with a plurality of openings 14, and having a lower arch shaped opening 15. This gate 13 is used to regulate and distribute the heat coming from the combustion chamber 6 through the opening 16 and passing the gate 17, which is provided with a lever 18 so as to shift the position of the gate 17 as desired.

The water cooled member 4 and the water cooled members 8 are cooled so as to regulate the heat and to keep the heat from reaching a temperature sufficient to ignite the pitch within the pitch hopper 11.

The steam heated base 9 tends to regulate the temperature of the pitch hopper 11 in order to heat the pitch within the hopper and still tend to keep the pitch within the hopper from reaching an undesirable temperature.

This steam heated base 9 may be heated in any ordinary way as by means of an ordinary inlet and outlet for steam shown as inlet and outlet 10.

The gate 17 above referred to may be cooled in any ordinary way; that is, the gate probably would be hollow with an ordinary inlet and outlet. The object of cooling this gate is to keep the same from warping or melting, due to the extreme heat subjected to the same.

By again referring to Figure 2 it will be seen that we have provided an opening 19 under the lower portion of the steam heated base 9. The object of this opening 19 is to provide means for admitting forced and heated air down the incline formed by the upper surface of the water cooled member 4. As the pitch becomes melted in the hopper 11 the same runs down the incline formed on top of the water cooled member 4 underneath the gate 17, and then into a diverging channel 20 where the liquid is subjected to a thorough mixing in the combustion chamber 6 by means of compressed air travelling through the pipe 21, the drum 22, and a plurality of outlets 23, which are formed

at right angles to the drum 22. Leading from the drum 22 we have provided a plurality of outlets 24 which are formed so as to converge of the air towards the center of the combustion chamber 6, where the combustion material is subjected to a thorough air mixing process.

By referring to Figures 1 and 4 it will be seen that these outlets 23 and 24 are 10 provided with valves 25 so as to regulate the amount of incoming air.

By referring to Figure 1 it will be seen that the perpendicular wall 26 incloses a boiler 27, and that the arched wall 28 joins the perpendicular wall 26 at right angles and is built back as far as the gate 13. The perpendicular wall 26 is provided with a plurality of openings 29 positioned directly above the opening 16.

20 It is understood that the pitch burner above described may be used for the purpose of heating other objects than the boiler 27 if so desired.

What we claim is:

25 In a device for burning pitch, a water

cooled member placed upon wall supports so as to form an incline, the lower end of which is provided with a diverging channel, two water cooled members positioned upon the upper and outer edges of the first mentioned water cooled member, a steam heated base arranged on said first mentioned water cooled member, an air opening in the bottom of said steam heated base, a hopper positioned upon said steam heated base, an 35 opening in said hopper for admitting pitch onto the first mentioned water cooled member, a gate in front of said opening, an air drum and a plurality of air outlets positioned so as to converge the direction of the 40 air and direct it beneath said diverging channel and valves for controlling said air outlets.

In testimony whereof we affix our signatures.

JOSEPH H. MURRAY.
McKINLEY WESSON.
